UNITED STATES PATENT OFFICE.

JEREMIAH ERWIN, OF CHICAGO, ILLINOIS, ASSIGNOR OF ONE-FOURTH TO BENJAMIN B. THORSEN, OF CHICAGO, ILLINOIS.

COMBINED CLOSURE AND SPREADER FOR LIQUID-CONTAINERS.

1,000,081.

Specification of Letters Patent.

Patented Aug. 8, 1911.

Application filed January 17, 1910. Serial No. 538,434.

To all whom it may concern:

Be it known that I, JEREMIAH ERWIN, a citizen of the United States, and a resident of the city of Chicago, in the county of Cook and State of Illinois, have invented certain new and useful Improvements in Combined Closures and Spreaders for Liquid-Containers; and I do hereby declare that the following is a full, clear, and exact description 10 of the same, reference being had to the accompanying drawings, and to the numbers of reference marked thereon, which form a part of this specification.

Difficulty is often experienced in the use 15 of liquids such as mucilage and other viscous fluids by the evaporation of the liquid constituents thereof permitting the solid constituents to gum upon or around the discharge orifice thereby sometimes wasting 20 considerable portion of the contents and rendering that remaining not conveniently available for use.

The object of this invention is to afford 25 a construction providing a fountain reser- voir or container for liquids, the closure for which acts when pressed inwardly to automatically spread the contents upon the surface to be treated.

It is also an object of the invention to afford 30 a construction adapted to be conveniently carried in the pocket without endangering the clothing through leakage of the container and to afford also a construction instantly available for use and by the 35 use of which the liquid is spread uniformly.

It is a further object of the invention to afford 40 a construction in which a rotational element serves both as a valve closure to prevent the loss or leakage of the contents 45 of the container and also as a spreader to spread the contents over the object to which applied.

The invention consists in the matters hereinafter described and more fully pointed 45 out and defined in the appended claim.

In the drawings: Figure 1 is a central longitudinal section of a device embodying 50 my invention, showing the same in a form adapted for pocket use. Fig. 2 is a similar 55 enlarged fragmentary section. Fig. 3 is a section on line 3—3 of Fig. 2. Fig. 4 is a bottom plan view of the same. Fig. 5 is a central longitudinal section illustrating a slightly modified construction of the closure or spreader. Fig. 6 is a similar enlarged

fragmentary longitudinal section taken at a right angle with that shown in Fig. 5, and showing the spreader or closure in elevation. Fig. 7 is a bottom plan view of the construction illustrated in Figs. 5 and 6.

60

As shown in the drawings: 1, indicates a container or receptacle shown as elongated in form and adapted for carriage in the pocket similarly with a fountain pen. Said container is integrally closed at one end and at its opposite end is internally threaded to receive therein the nozzle 2, which, as shown, is provided at its upper end with a sleeve 3, adapted to fit in the receptacle and below said sleeve is threaded to engage the screw 70 threads in said receptacle and is provided below said threads with a collar 4, of the same diameter as the receptacle and finishing flush therewith.

The lower or discharge end of the nozzle 75 is shaped, spun or otherwise formed to afford a restricted orifice, as shown in Figs. 1, 2, and 4, and movable in said nozzle and engaged at its upper end therein by means of a spring 5, is a stem 6, the lower end of 80 which is forked or shaped to afford downwardly directed claws 7, which engage loosely about a ball closure 8, which fits in the restricted orifice in said nozzle and under the action of said spring affords a tight closure 85 therefor. The portion of the periphery of said ball, however, projecting through said orifice permitting the flow of the liquid past the ball when the same is pressed inwardly by contact with the surface to be 90 treated. As shown also, a cover cap 9, is provided to cover and protect the nozzle end of said receptacle, said cover cap being of a size to engage on a suitable seat therefor at the upper end of said container when the device is ready for use.

In the construction illustrated in Figs. 5 to 7 inclusive, the nozzle 10, affords a much larger portion of the container than in the construction before described and as shown, 100 is provided with a central sleeve 11, communicating therein, which threads into the barrel 12, of the container which also, as shown, is closed at its outer end. Said nozzle is extended transversely the barrel 12, 105 on the end of which it is engaged by threading the sleeve therein and as shown, is provided with a relatively long and narrow orifice on the side thereof opposite said barrel and extending the longest way of said nozzle.

110

zle. A stem 13, is engaged by means of a spring 14, with the inner end of the sleeve 11, and at its outer end or that extending into the nozzle is provided with a yoke 15, 5 the ends of which are apertured to rotatably engage gudgeons 16, one at each end of a cylindric closure and spreader 17, which, as shown, is also rounded at its ends to afford a tight joint along both sides and at the ends 10 inclosing the nozzle.

The operation is as follows: When the receptacle or container is filled and the nozzle threaded back into place, the spring 14, acts at all times to press the stem and rounded 15 closure or spreader outwardly to afford a positive closure for the discharge orifice. Inasmuch as the orifice through the nozzle is shaped complementally with a section of the closure which fits therein, a tight joint is 20 afforded thereby entirely precluding leakage when the device is not in use and of course, wholly preventing evaporation of the more liquid or volatile contents of the device.

When it is desired to apply the liquid to 25 any surface the closure or spreader is pressed lightly thereon, forcing the same inwardly sufficiently to clear the nozzle and is moved along on said surface thereby rotating the spreader on the end of the stem which engages the same, thus delivering a thin film 30 of the liquid onto the surface to be treated. This will be the more readily appreciated from the fact that the inner surfaces of said closure or spreader are at all times immersed 35 in the liquid, thus as the spreader is rolled along the surface to be treated, delivering

the fresh liquid from within the container thereon.

Of course, details of the construction may be varied. If desired, either form of the device may be employed as a closure for bottles intended for any kind of liquid for obviously it is not essential that the particular form of the barrel or container proper be maintained, and, of course, the nozzle may 40 assume any desired form in which may be installed a closure adapted to be rolled along the surface to be treated and to spread liquid from said container thereon. I therefore do not purpose limiting this application for 45 patent otherwise than necessitated by the prior art.

I claim as my invention:

A device of the class described embracing a reservoir, a nozzle connected therewith, a rolling closure within and slightly protruding beyond said aperture in said nozzle and acting when pressed inwardly to deliver a portion of the fluid contained in said reservoir, a spring pressed bar in said nozzle 55 and a plurality of fingers or claws on said bar between which said closure is adapted to roll, said fingers acting to prevent excess material from adhering to said roller.

In testimony whereof I have hereunto subscribed my name in the presence of two subscribing witnesses.

JEREMIAH ERWIN.
